US0D1066259S

(12) **United States Design Patent** (10) Patent No.: **US D1,066,259 S**
(45) Date of Patent: ** Mar. 11, 2025

(54) **ELECTRICAL CONNECTOR**

- (71) Applicant: **FCI CONNECTORS DONGGUAN LTD.**, Dongguan (CN)
- (72) Inventors: **Hua-Kun Wei**, Dongguan (CN); **Yi-Lin Liu**, Dongguan (CN)
- (73) Assignee: **FCI CONNECTORS DONGGUAN LTD.**, Dongguan (CN)
- (**) Term: **15 Years**
- (21) Appl. No.: **29/860,885**
- (22) Filed: **Nov. 23, 2022**

Related U.S. Application Data

- (62) Division of application No. 29/687,528, filed on Apr. 12, 2019, now Pat. No. Des. 975,024.

CLAIM

The ornamental design for an electrical connector, as shown and described.

DESCRIPTION

FIG. 1 is a top, front, left side perspective view of an electrical connector according to our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the figures represent portions of the electrical connector that form no part of the claimed design.

1 Claim, 7 Drawing Sheets
